UNITED STATES PATENT OFFICE

JOHN D. HILLIARD, OF GLENS FALLS, NEW YORK, ASSIGNOR TO GENERAL ELECTRIC COMPANY, A CORPORATION OF NEW YORK

ARC EXTINGUISHING FLUID

No Drawing.

Application filed November 26, 1929. Serial No. 410,008.

My invention relates to an arc-extinguishing fluid and more particularly to such a fluid for use in fluid-break circuit interrupters enclosed within a tank or housing.

5 The use of a dry mineral oil as the arc-extinguishing and insulating medium in circuit breakers of large interrupting capacity is well known and commonly accepted practice. The oil circuit breaker design, however, has been rendered difficult in many respects by the frequently enormous explosive pressures developed within the switch tank or housing during interruption of the circuit. These tremendous pressures are caused in part 10 by the generation of large volumes of gases by the dissociating action of the power arc on the oil. The gaseous pressures so generated may be high but it is possible to design a switch housing so that it will withstand the pressure caused by arcing of reasonable duration and intensity. Due, however, to the fact that the gases so generated may be highly inflammable or of an explosive nature another source of excess pressure, namely a detonation or secondary explosion, is present. In the usual type of oil switch, there is an air space in the switch tank above the oil level and it is within this space that the inflammable gases collect. Accordingly, if these 15 gases are ignited by a static spark, or by other causes a resulting detonation or secondary explosion may produce such disruptive pressures within the tank that it fails. A severe detonation also may cause excess vibration 20 of the tank so that the porcelain or other insulating material of the bushings for the lead-in conductors is cracked or broken off. The gas which is formed when an arc is 25 drawn in oil is a mixture of hydrogen, methane, acetylene ethylene and small quantities of other gases. Accordingly, there is a 30 possibility of detonation in the gaseous charge which may produce a pressure or concussion beyond that produced in the ordinary gas explosion and is, therefore, more dangerous to the structure of the breaker.

The arc in the oil causes the dissociation of 35 part of the oil, assumed to be decane, into hydrogen and hydrocarbon gases, the heat produced by the arc also dissociating the

molecules of the gases, and it is during the recombination of the atoms with the oxygen in the air space above the oil that detonation is liable to take place. It is possible, of course, that the quantity of acetylene gas 55 produced in the breakers may be comparatively large because the circuit breaker oils is high in the paraffin series and also is subjected to the high temperature of the arc. Acetylene, being an endothermic gas, can detonate under pressure alone and a mixture of acetylene and air has a greater range within which it may explode than any other mixture so that there is a real danger of detonation.

The destructive consequences of a switch 60 failure involving rupture of the oil tank and projection of the burning oil and gases throughout the switch station are well known to designing engineers and operators and are guarded against in every practical manner known.

65 It is an object of my invention to provide an arc-extinguishing fluid which shall produce a non-detonating gas when the fluid is acted upon by an electric arc.

70 It is a further object of my invention to provide an arc-extinguishing fluid comprising a mixture of a mineral oil and a detonation suppressor for eliminating the disruptive or concussive effect of a detonation in a 75 circuit breaker tank.

76 My invention will be more fully set forth in the following description and the features of novelty which characterize my invention will be pointed out with particularity in the 80 claims annexed to and forming a part of this specification.

85 In accordance with my invention, the detonating effect of the gases generated by the action of an arc on the oil is eliminated by 90 mixing in suitable proportions with the usual dry circuit breaker oil a detonation suppressor thereby increasing the effective capacity of the circuit breaker. An example of a detonation suppressor is aniline which when 95 mixed in suitable proportions with the oil does not adversely affect the dielectric strength thereof to a dangerous degree. Benzene, toluene and xylene act in a similar manner as aniline although the latter substance 100

is preferred. Detonation suppressors per se, as well as the relative weights thereof for suppressing detonation, are well known and it is not believed necessary to enumerate further examples other than to state that my invention is not limited to the specific detonation suppressors above mentioned.

When the arc-extinguishing fluid comprising a detonation suppressor is to be used in a single tank in which the switch contacts are bridged by a single bridging member, the detonation suppressor should have fairly good dielectric characteristics, as for example aniline, so that the dielectric strength of the mixture shall not be so low that there is danger of shorting the contacts. By way of example but without limitation of my invention thereto the dielectric strength of the mixture should not be below 20,000 volts per 0.2 inch. In certain other types of circuit interrupters wherein a separate container is provided for each movable contact, as where the movable contact separates from its coacting contact within the arc-extinguishing fluid and thereafter is withdrawn to a position in air above the surface thereof, the dielectric strength of the mixture is not necessarily so important, so that in this case the most effective and suitable detonation suppressor may be used. It shall be understood that my invention is not limited to a mixture of oil with a single detonation suppressor but that two or more of said suppressors may be mixed with the oil without departing from the spirit of my invention.

What I claim as new and desire to secure by Letters Patent of the United States, is:

1. An arc-extinguishing fluid consisting of a mixture of a combustible mineral oil and a detonation suppressor.
2. An arc-extinguishing and insulating fluid comprising a mixture of a combustible dry mineral oil and a substance for preventing detonation of gases formed by the action of an arc on said oil, said mixture having comparatively high dielectric strength.
3. An arc-extinguishing fluid for fluid-break circuit interrupters having a tank subject to expansive pressures during circuit interruption comprising a mixture of a combustible mineral oil and a substance for preventing detonation of gases produced by the action of an arc on said oil.
4. An arc-extinguishing and insulating medium for a circuit interrupter of the fluid-break type, comprising in combination a mixture of a detonation suppressor and a substantially dry combustible mineral oil, the dielectric strength of the mixture being at least 20,000 volts per 0.2 inch.

In witness whereof, I have hereunto set my hand this 23rd day of November, 1929.

JOHN D. HILLIARD.
